UNITED STATES PATENT OFFICE.

ARTHUR S. BALDWIN, OF BALTIMORE, MARYLAND.

PERCUSSION-FUSE.

1,311,673.

Specification of Letters Patent. Patented July 29, 1919.

Application filed February 7, 1917. Serial No. 147,111.

To all whom it may concern:

Be it known that I, ARTHUR S. BALDWIN, a citizen of the United States, residing at Baltimore, in the State of Maryland, have 5 invented new and useful Improvements in Percussion-Fuses, of which the following is a specification.

This invention relates to improvements in percussion fuses for shells or projectiles, and 10 has particular reference to that class of fuses known as inertia-operated fuses where in the firing pin is normally held in a safety position and becomes armed upon the shell or projectile being fired from a gun.

15 The present invention is directed to improved means for normally retaining the firing pin in the so-called unarmed or safety position, and to an improved means for preventing the firing pin and its associated devices from creeping forward toward the primer cap during the flight of the projectile or shell.

Another object of the invention is to provide an improved construction of fuse that 20 will be simple in construction, and inexpensive to manufacture, and which will dispense with the use of shear pins which latter, when sheared often, are liable to frictionally engage the parts, and interfere with 25 the freedom of movement that is necessary for a certainty of action.

With these, and other objects in view, the invention is illustrated in the accompanying drawing wherein,

30 Figure 1, shows the improved fuse structure in longitudinal section,—the firing devices being shown in the safety position.

Fig. 2, illustrates the same in cross-section,—the section being taken on the line 40 2—2 of Fig. 1.

Fig. 3, shows another view of the fuse device in longitudinal section,—the firing devices being in the armed position, and

Fig. 4, illustrates a cross-sectional detail 45 through the same,—the section being taken on the line 4—4 of Fig. 3.

Referring to the drawing the numeral 5, designates the case or stock having exterior screw-threads 6, and an interior circular chamber 7, extending longitudinally therein. The inner end of the chamber 7, is closed, by a cap 8, in which is located a primer 9, and an additional powder charge 10, which latter, when detonated, fires the main charge 55 in the shell-body in the usual way.

A plunger body 11, is positioned in the chamber 7, of the case or stock; is formed of metal, and has a cross-sectional shape in conformity to the shape of the said chamber. This plunger body has a central upper passage 12, which extends longitudinally therein and is also provided with a larger longitudinal passage 13, below said passage 12, for a purpose presently to be explained.

60 The bottom of the plunger body also has a circular cavity 14, of a greater diameter than the passage 13, whereby to produce an annular shoulder 15, around the base of the passage 13, for a purpose also presently to be explained.

70 In the present instance, the circular cavity 14, of the plunger body contains a bushing body 16, which latter has a central passage 17. This bushing body has a lower beveled end 18, which projects below the lower end of the plunger body 11, and the plunger body has its lower end contracted or upset inwardly into locking engagement with the beveled end 18, of the bushing body whereby to effectively lock the two bodies together, and against independent longitudinal movement.

75 At the inner end of the circular cavity 14, and between the shoulder 15, and the upper or inner end of the bushing body, I place a disk 19, which latter separates the circular cavity 14, from the longitudinal passage 13,—the disk being of sufficient diameter to project beneath the annular shoulder 15.

80 The firing device proper, has the form of a stem with a plurality of diameters in cross-section,—the upper firing-pin end 20, forming the pin proper, and being of a diameter to fit the upper passage 12, of the plunger body and of sufficient length to extend 85 through the passage 13, and into the upper end of the central passage 17, of the bushing body. This upper end 20, also passes through a perforation in the disk 19,—the perforation being of sufficient diameter to 90 effect a snug fit with the end 20, of the stem. Immediately below the disk 19, the stem increases in diameter so that a shoulder 21, is formed on the stem, and said shoulder seats or engages the under side of 95 the disk and is thereby held against movement in a direction toward the primer 9.

100 The lower end 22, of the firing pin stem projects below the end 18, of the bushing body and has a beveled extremity 23, which 110

seats against the end wall 24, of the stock or case chamber 7, as clearly seen in Fig. 1, of the drawing.

The disk 19, which is interposed between the shoulder 15, of the plunger body and the shoulder 21, of the firing-pin stem is preferably of a material such as copper that may be punctured by the stem-shoulder 21, under the action of a blow or shock, 10 such as will be imparted when the fuse is projected from a gun in a shell.

The inner end of the plunger body is preferably provided with an annular groove or seat 25, while the closing cap 8, at the inner end of the fuse has a coincident annular groove 26, and a coiled spring 27, is seated in these annular grooves and is normally compressed therein between the cap and plunger body.

20 In operation the parts of the fuse, when attached to a shell, have the relative positions shown in Fig. 1, of the drawing, at which time, the inner grooved end of the plunger body is seated against the closing cap 8, and the spring 27, held compressed. This position of the parts is effected through the firing pin stem, whose outer end is seated against the end wall 24, of the chamber 7, and whose shoulder 21 is seated 30 against the under side of the puncturable disk 19. When in this, so-called safety position, the firing-pin end 20, of the stem has position in the passage 12, of the plunger body but sufficiently spaced from the primer 35 9, to be kept from contact with the latter.

When the shell is fired, the case or stock is driven forward with such force, while the plunger body lags, that the shoulder 21, of the stem is driven through the disk 19, thereby punching a washer-like portion 28, shown in Fig. 3, from the disk and allowing the plunger body and bushing body to assume a rearward position in the chamber 7, which latter position is aided more or less by the 40 spring 27. When assuming this latter or rearward position, the beveled end 18, of the bushing body is driven with sufficient force against the end wall 24, to cause it to become upset, as at 29, in Fig. 3, and thereby 45 rigidly engaged with the beveled end 23, of the firing-pin stem, so that thereafter the stem, plunger-body and bushing-body must move together. This latter position is what is termed the armed position, because the 50 end 20, of the firing pin is projected beyond the plunger body and may strike the primer when the flight of the shell is suddenly arrested, as when it contacts with an object.

During the flight of the shell, and after 60 the firing devices have become armed, it has been found in practice that there is a liability of the firing devices, including the plunger body and pin, creeping forward and coming in contact with the primer 9, which 65 may detonate the latter and cause a prema-

ture explosion of the shell. This undesirable creeping-forward action, is therefore eliminated in my improved fuse because of the interposition of the spiral spring 27, the spring however being only of sufficient power to prevent creeping, but insufficient to prevent the forward movement to cause the pin to detonate the primer when the shell strikes and its flight is suddenly arrested. 75

Having described my invention what I claim and desire to secure by United States Letters Patent is,—

1. In a fuse device the combination with a case having a chamber, of an explosive element; a plunger in said chamber and having a passage therethrough; a bushing body in the plunger and having a passage coincident with the plunger passage; a firing stem extending through the bushing body passage; and projecting into the plunger passage; means between the bushing body and plunger and engaging the firing stem and yielding means to hold the stem against creeping toward the explosive element during flight 90 of the shell.

2. In a fuse device the combination with a case having a chamber, of an explosive element; a plunger in said chamber and having a passage therethrough; a bushing body in the plunger and having a passage coincident with the plunger passage; a firing stem extending through the bushing body-passage and projecting into the plunger passage; a disk interposed between the bushing body 95 and the plunger and engaging the firing stem said disk being cut by the plunger upon the shock of firing, and means for locking the bushing body and firing stem together when the disk is cut. 100

3. In a fuse device the combination with a case having a chamber, of an explosive element; a plunger in said chamber and having a passage therethrough; a bushing body in the plunger and having a passage coincident with the plunger passage; a firing stem extending through the bushing body-passage and projecting into the plunger passage; a disk interposed between the bushing body and the plunger and engaging the firing 110 stem said disk being cut by the plunger upon the shock of firing, and yielding means to hold the stem against creeping toward the explosive element during flight of the shell. 115

4. In a fuse device the combination with a case having a chamber, of an explosive element; a plunger in said chamber and having a passage therethrough; a bushing body in the plunger and having a passage coincident with the plunger passage; a firing stem extending through the bushing body-passage and projecting into the plunger passage; a disk encircling the firing stem in said passages and interposed between the stem and the plunger to prevent movement between 125 130

the plunger and stem; means for locking the plunger, bushing body and stem together upon the shock of firing and a spring between the plunger and explosive element to prevent the firing stem creeping toward the explosive element during flight of the shell.

5. In a fuse device the combination with a case having a chamber, of an explosive element; a plunger-body in said chamber said plunger-body having a central passage at its inner end, an enlarged cavity in its opposite end and an intermediate passage larger than said passage and smaller than said cavity; a bushing-body in the enlarged cavity of the

10 plunger-body and projecting from the end thereof said bushing-body having a central

15

longitudinal passage; a puncturable disk in the inner end of the plunger-body cavity and held therein by the bushing-body and a stem extending through central passage of the 20 bushing-body and having a reduced end that passes through the disk and projects freely through the intermediate passage and enters the smaller central passage of the plunger-body.

25

In testimony whereof I affix my signature in the presence of two witnesses,

ARTHUR S. BALDWIN.
